UNITED STATES PATENT OFFICE.

CLARENCE E. SMITH, OF BROWNSBURG, INDIANA.

RAIN-INDICATOR.

1,137,674.

Specification of Letters Patent.

Patented Apr. 27, 1915.

Application filed April 15, 1914. Serial No. 832,039.

To all whom it may concern:

Be it known that I, CLARENCE E. SMITH, a citizen of the United States, residing at Brownsburg, in the county of Hendricks 5 and State of Indiana, have invented certain new and useful Improvements in Rain-Indicators; and I do hereby declare the following to be a full, clear, and exact description of the invention, such as will enable 10 others skilled in the art to which it appertains to make and use the same.

This invention comprehends certain new and useful improvements in rain indicators and has for its primary object to provide a 15 device of this character which will be constructed in such manner as to readily indicate rain.

Another object is to provide a device of 20 this character, the principal portion of which may be positioned outside of a window and will be constructed in such manner that the first few rain drops collecting therein will cause operation of the device to give a signal and thereby notify the occupants of the house that rain is falling.

Another object is to provide a device of 25 this character which will be of extremely simple construction, and operation and cheap to manufacture.

30 A further object is to provide an electric rain signal or indicator including a cup positioned upon a pivoted contact member and inclosed in a casing having a depressed upper portion with an opening in its lowermost portion directly above the cup, whereby the raindrops will be collected and guided to the cup to cause the same to move downwardly and thereby operate the pivoted contact member to throw the latter into 35 engagement with a second contact member and thereby complete an electric circuit to give the signal.

This invention has for a still further object to generally improve and simplify the 40 construction and operation of devices of this character and increase the efficiency thereof without increasing the cost of the same.

With these and other objects in view, as 45 will become more apparent as the description proceeds, the invention consists in certain novel features of construction, combination and arrangement of parts as will be hereinafter more fully described and claimed.

50 For a complete understanding of my invention, reference is to be had to the following

description and accompanying drawings, in which—

Figure 1 is a diagrammatic view of the complete device, Fig. 2 is an elevational view 60 of the device, Fig. 3 is a longitudinal section through the casing with the operative parts positioned therein, Fig. 4 is a transverse sectional view on the line 4—4 of Fig. 3, and Fig. 5 is an elevational view at right angles 65 to Fig. 2.

Referring in detail to the drawings by numerals, 1 designates the casing, the opposite ends of which are inclined inwardly and downwardly, as shown at 2, and connected at their lower ends to the inwardly and downwardly inclined outer wall 3 of said casing. The rear wall 4 is preferably vertical and the top 5 is depressed, as clearly shown in the drawings, and has an opening 75 6 at its lowermost portion, the purpose of which will presently appear.

The casing 1 is adapted to be supported in position by means of the battery 7 positioned upon the horizontal arms 8 of the 80 right angled supporting bracket 9, the upstanding angle of which is secured against the rear vertical wall 4 of said body 1. It will therefore be seen that as the casing 1 is formed of light material, the weight of 85 the battery 7 will serve to support said casing 1 in upright position.

The upstanding angle of the right angled bracket 9 also serves to support the bell 10 which has electrical connection with the battery 7, the wire 11 from one pole of the battery 7 being connected with the bell 10 before being extended through the rear wall of the casing 1 and connected with the stationary contact point 12 within the casing 1. 95 The wire 13 from the other pole of the battery is also extended through the rear wall of the casing 1 and connected with the pivoted contact member 14, which is pivotally mounted intermediate its ends, upon the 100 supporting bracket 15 secured to the inner face of one wall of the casing 1, one end of the pivoted contact member 14 being adapted for engagement with the stationary contact member 12 to complete the circuit and ring 105 the bell 10 upon downward movement of the opposite end of said pivoted contact member, upon which opposite end is positioned the cup 16. The pivoted contact member 14 is positioned within the casing 1 in such 110 manner that the cup 16 is directed beneath the opening 6, whereby raindrops falling

upon the depressed top 5 of the casing 1, will drop through the opening 6 and into the cup 16 and thereby cause downward movement of the cup, compelling the pivoted contact member 14 to swing upon its pivot and engage the free end thereof with the stationary contact member 12, as previously stated, thereby causing complete operation of the device to give a signal and notify the occupants of the house that rain is falling.

The device may be readily raised and transported from place to place by means of the handle 17 secured to the back of the device near the upper edge thereof, by means of the spaced supporting brackets 18, by which the opposite ends of said handle 17 are carried.

It will be understood that the bell 10 or other signal employed in this device may be positioned within the house or at any other place desired instead of upon the right angled bracket 9, if preferred. It will also be understood that other minor changes in the details of construction and arrangement of parts may be made within the scope of the appended claim without departing from the spirit of my invention or sacrificing any of the advantages thereof.

Having thus described my invention, I claim:

A device of the class described comprising

Copies of this patent may be obtained for five cents each, by addressing the "Commissioner of Patents, Washington, D. C."

a casing having a depressed top with an opening in its lowermost portion, a pivoted contact member within said casing, means carried by said casing for supporting said pivoted contact member, a stationary contact member spaced from said pivoted contact member, a cup formed on said pivoted contact member and positioned beneath said opening, whereby drops of rain falling upon the top of the casing will be conducted to the cup to cause the same to move downwardly and thereby engage the pivoted contact member with the stationary contact member, a battery, electrical connections between one pole of said battery and the stationary contact member, electrical connections between the opposite pole of said battery and the pivoted contact member, whereby a circuit will be completed upon engagement of the movable contact member with the stationary contact member, and a signal within the circuit and adapted to be operated upon engagement of said pivoted contact member with the said stationary contact member.

In testimony whereof I affix my signature in presence of two witnesses.

CLARENCE E. SMITH.
